CLAIM

The ornamental design for a foamer pump, as shown and described.

DESCRIPTION

FIG. 1 is a front perspective view of the foamer pump.

FIG. 2 is a rear perspective view of the foamer pump.

FIG. 3 is a front view of the foamer pump.

FIG. 4 is a rear view of the foamer pump.

FIG. 5 is a right side elevational view of the foamer pump.

FIG. 6 is a top view of the foamer pump; and,

FIG. 7 is a bottom view of the foamer pump.

The broken line portions of the disclosure are for illustrative purposes only and form no part of the claimed design.
